ROTARY FORCE-FEED PISTON PUMP

Application filed February 12, 1929, Serial No. 339,408, and in Germany January 31, 1928.

This invention relates to rotary piston force feed lubricating oil pumps with a plurality of pistons whose stroke is separately variable, and having several force feed points and which are especially suitable for use in motor vehicles.

There are already known piston pumps in which the piston, while the pump is in operation, is rotated around its longitudinal axis and while it rotates is at the same time displaced axially against the action of a spring. The axial displacement produces the movements of the piston. The movements of the piston may be determined on the one hand in the known manner whereby at one end of the hollow piston an annular ring face is formed as a cam face which, during the rotation of the piston is following in a curve which is formed to correspond with the length of the stroke. On the other hand, the said curve may also be provided on the annular ring face of the piston by forming this in a plane of section taking an inclined position to the axis, and which for instance may bear on a fixed stud, so that in this manner the movements of the piston are produced, or else the curve is formed by a corresponding groove which has been formed in position and in which engages a gudgeon pin. In each of the first named instances, a compression spring which is positioned within the hollow piston is called upon to press the piston always against its curve in order to produce the movement of the piston, whereas, when the piston is formed with the groove drilled into the same, the spring may be omitted, because in such a case, by reason of the engagement of the gudgeon pin in the groove, the piston is positively guided by each side of the groove.

A force feed lubricating oil pump which is constituted in this manner will always deliver an equal quantity of oil. Sometimes it will, however, be necessary to vary the quantity of oil delivered which will prove of especial advantage in those cases in which the piston pump, in the shape of a small oil pump, is designed to serve for the oiling of the cylinders of combustion engines. The variability of the quantity of oil delivered will permit the use of the same size pump for com-

bustion engines of varying size, seeing that the quantity of the oil delivered may always be adjusted in conformity with the supply of oil required by the cylinders of the combustion engines, so that an excessive oil supply is definitely avoided which will, of course, result in a very economical oil consumption.

Pumps of the usual type now known to the art possess as a rule, only one or at the most two force feed points. In the main, however, we only find that type of pump in which one suction point and one force point are crowded into a narrow space, in a convenient place of the engines, as for instance in motor cycle engines.

At the present stage of engineering and of the construction of combustion engines, and especially of those which are designed to serve for use in motor cycles, the provision of only one force feed point for supplying the oil in the cylinder of a combustion engine will not, as a rule, be sufficient, for there are several other places in a motor vehicle which require lubrication, as for instance, the chain, or the faces of the cams in motor vehicles with upper valve motion. With the present form of pump having one force feed point only, one or more pipes of suitable diameter are branched off for the purpose of supplying the above mentioned oil consuming places with oil, which is after all only an emergency arrangement, because whenever one has to deal with a total oil supply which is of some importance, this arrangement will prove to be unable to supply all the oil consuming places with that quantity of oil which they absolutely require and it will thus happen that one or the other of these oil consuming places will be supplied with oil inadequately.

Therefore, we have designed rotary piston pumps with several force feed points which are all subject to the action of the moving piston by providing for instance the piston at both ends with suitable slots or grooves which are drilled into the same and which produce the action of suction and of forcing and by connecting these openings in the piston to suitable tubes supplying the oil to the various places of oil consumption. At the same time the one, two or even more pis-

tons are guided, with regard to their longitudinal movement, with positive motion and we have provided the same with a throw controlling device which is fit and adapted while the pump is in operation, or at rest, to vary the length of stroke of the pistons and to obtain thereby a faultless adjustment of the throw and eliminate the usual inconveniences, so that the quantity of oil which is being delivered may be so adjusted that it is each time coping with the quantity of oil which is actually required, and which will remain always the same during the whole time the throw controlling device is set and adjusted to that particular quantity of the supply.

A particular advantage and an additional characteristic of the present invention lies in the location of several pistons in one and the same axial direction of the same. The pistons are connected by suitably designed coupling means with the driving piston, so that only one driving spindle is needed for moving the totality of the pistons. The adequately designed and constructed coupling means has for its object to accomplish any desired variations of the throw, regardless of the coupling together of the pistons, so that the varying of the throw of one of the pistons will not interfere in any way with the other pistons. In this manner there is provided a rotary piston pump which, with a minimum expenditure of material and the smallest admissible number of component parts, makes use of only one drive and one suction point, and supplies simultaneously two, three or more oil consuming places with oil, and the whole assembly may be made of such small dimensions that when fitted to a motor cycle engine or the like, the accessibility of the engine is not impaired.

The invention is illustrated in Figs. 1 to 10 of the accompanying drawing, and in which Fig. 1 is a front elevation, Figs. 2 and 4 each show a longitudinal view through the pump with the pistons in different positions, while Fig. 3 is a cross sectional view of the pump about the line A—B of Fig. 2 and Fig. 5 is a cross sectional view of the pump about the line C—D of Fig. 4. Figs. 6—10 are showing various positions at which the throw controlling device has been set within the grooves which are formed in the pistons.

In the embodiment of our invention, which is shown in the drawing, a rotary pump with three force points and one throw controller device for each piston, has been adopted.

In the pump casing 1 a driving spindle 2 is putting in rotation two or three pistons by means of an endless screw and worm gear. The bearings of the pistons are closed by screws 5 and the interposing of a packing 6, so that the pistons on the one hand are prevented from falling out and on the other hand the escape of any oil is prevented. The

piston 3 at its two ends is provided for instance with grooves 7 and 8, which start up the pumping operation whenever the piston is rotated or displaced in the direction of its axis within the boring. In a suitable place there is formed in the piston 3 a slanting annular groove 9, in which engages the throw controlling device which imparts to the piston a positive motion. The piston 3 has the function of sucking the oil which is flowing from a point of use and passing it to the suction port 10, disposed at the rear of the two pistons (shown by dotted lines in Figs. 2 and 4 and clearly illustrated in Fig. 3) through the boring 11 on the piston being suitably displaced longitudinally towards the right, and on rotating the piston to a still greater extent to force the same through the tube 12 into the inspection chamber. From here the oil is again sucked by the groove 7, provided on the other end of the piston, and is forced into the boring 14, which communicates with the force point 15, which is located directly opposite the suction port 10. In this manner the force feed point 15 may be controlled through the inspection chamber.

The piston 4 is supplying the force point 16 with oil, in such a way that the oil passes from the boring 11 into a longitudinally extending boring 18. By the boring 18 and the groove 19 on the right hand end of the piston 4, the oil is sucked in conformity with the throw of the piston and is delivered to the force point 16.

As a third piston there is provided in the casing 1, the piston 20 which, however, is not moved directly by the driving spindle 2 but by the piston 4, the piston 4 having on the left hand end a transversely extending groove 21, in which engages a spring 22 which is provided on the right hand end of the piston 20. In this manner the piston 20 is coupled with the piston 4 and accomplishes the same rotary motion as the piston 4 itself.

The left end of the piston 20 presents the distinctive feature of that pump in the form of a groove 23, so that the piston 20, in performing the appropriate motions (rotation and displacement) will suck the oil by the boring 24 which communicates with the analogous longitudinal boring 17 which is disposed in front of the piston and forces the oil into the place of consumption 25. The pistons 4 and 20 are likewise provided with slanting annular grooves 26 and 27 with which engage the controlling devices by which on the one hand the pistons are guided with positive motion in their longitudinal movements and on the other hand are causing the variations in the length of their stroke. The two pistons are coupled in such a manner with each other that the slanting annular grooves 26 and 27 expand parallel in respect to one another and the positive motion and the longitudinal displacement of

the two pistons incidental thereto, (by reason of the position of the slanting grooves) are accomplished always in the same direction and thus they do not work in opposition to each other. The guide of the slot and key in the coupling need thus only be of the length of the stroke of the coupled pistons, because the variation in the length of the stroke may on the one hand be of such an amount as the 10 available total length of the stroke of pistons (if the curve is being varied in such a way that the pump is not delivering any oil the variation of the curve corresponds to the total length of the stroke) whereby it is obtained that the total length of the two pistons 4 and 20 which are coupled with each other will not be excessive. The characteristics of the pump described heretofore are shown in Fig. 2 and present the position of 20 the pistons after having completed the suction and forcing motions with the pump working at full capacity in all force points.

In Fig. 4 the corresponding parts of the pump are designated with like reference numerals, but the positions are different from those shown in Fig. 2 which is due partly to the turning movement of half a revolution given to the pistons and partly to the change in the position of the controlling device (variation in the length of the stroke). The change in the position of the stroke or throw controlling device is represented in Figs. 1 and 5.

On the frontal side of the pump casing are 25 fitted in convenient places for each piston (3, 4 and 20) pointers 28, 29 and 30, each of them being arranged on dials 31, 32 and 33, which enables the operator to read off readily from the scale the variations in the position 40 of the pistons. The pointer 28 indicates the full capacity of the piston 3, while the pointer 29 indicates half the full capacity, and the pointer 30 only about one fourth part of the full capacity of the pistons 4 and 20 respectively. The controlling device by itself consists in its internal construction of a stud 34 which being formed with various steps is conveniently seated in the casing 1 and which is provided on one end with the pointer and 45 on the other end with two curves 35 and 36 which engage in the annular grooves (9, 26 and 27) of the pistons (3, 4 and 20). The said curves are shaped to form ellipses and they are positioned with their axes at right angles 50 to each other. In this manner there is imparted to the pistons the positive motion above mentioned with regard to their longitudinal movements and the rotation of the curves permits the variation of the stroke, 55 through which however, the positive motion is not impaired. (This is described still more in detail hereinafter.) The rotated curves are shown in Fig. 5 in the lower controlling device and are clearly illustrated. 60 The studs 34 of the throw controlling device

are firmly secured against independent longitudinal displacement, as well as against an independent rotary motion whenever a variation in the stroke is not intended, by a disc 37 which is imbedded in the casing and secured to the same by means of screws 38. Only after having loosened the screws 38 will the stud 34 allow rotation by means of the pointer carried by the stud and thus the variation of the length of the stroke.

In Fig. 4 is shown in the main, apart from the other component parts of the pump already mentioned, the change in the position of the two coupled pistons 4 and 20 relative to each other, this change corresponding to the variation of the throw represented in Figs. 1 and 5. From Fig. 4 it is plainly seen that the guiding of the coupling in the space 39 is still ample, even in the case of a very large variation of the throw, in order to ensure a faultless transmission of the moment of torsion from the piston 4 to the piston 20, while however, the length of the two pistons coupled with each other is such that the total length of the pump remains a reasonable one.

It is at once evident that the piston 3, by providing similar coupling means, will be able to accomplish the transmission of the moment of torsion to a fourth piston, so that in this manner a fourth force point may be created. By suitable construction of the piston additional pistons may be axially connected up by means of couplings of the kind such as have just been described, all of which, however, can be supplied with oil from one suction point only, and all the pistons can be driven by one and the same driving spindle (spindle 2).

Now, hereinafter is described the special part which characterizes the pump, viz., the throw controlling device with its function and action. The grooves which are formed on the pistons 2, 4 and 20 are formed and arranged in such a way that the groove 40 is drilled in a vertical position with respect to the axis of the piston, while the groove 41 is extending in a slanting position with respect to the axis. The groove 40 is narrower and deeper than the groove 41 and the difference between the width of the two grooves represents the length of the throw. The walls of the groove 40 meet at two opposite points of their path with the walls of the groove 41. Thus the groove 41 constitutes the throw curve groove. With these grooves 40 and 41 and 41 engage the suitably formed curves (ellipses) 35 and 36 and disposed on the throw controlling member and which are positioned crosswise to each other, so that the short axis of the ellipse 35 is equal to the large axis of the ellipse 36. The large axis of the ellipse 35 corresponds to the width of the groove 41 while the large axis of the ellipse 36 (equal to the short axis of the ellipse 35) corresponds

to the width of groove 40. Whenever the throw controlling member 34 with the curves 35 and 36 is placed in such a position that the large axis of the ellipse 35 is engaging 5 in its entire length with the walls of the groove 41, the complete stroke of the piston will be accomplished by reason of the positive action of the grooves. The short ellipse 36 engages in the groove 40 (the spacing of 10 the ellipse corresponds to the depth of the grooves) but same does not exert any effect because the location and position of the grooves and the ellipse are such that they cannot counteract or act in opposition to the 15 normal throw of the piston.

The maximum quantity which can be delivered by the pump will be attained by the 20 position of the curves (ellipses) 35 and 36 which they take between the grooves 40 and 41 as is shown in Figs. 6, 7 and 8. As already explained the curve 35, inasmuch as the large axis of the same is in its entire length in engagement with the groove 41, will provide a complete throw of the piston. 25 How this can be achieved is shown in Figs. 6, 7 and 8. After having secured member 34 of the throw controlling device both against axial displacement and against rotation, the pistons are compelled, according to the 30 degree of inclination of groove 41 and of the compulsory guiding means of the curve 35, to take advantage of the difference between the inclined position of the walls of the groove 41 and the fixed guiding means 35 for 35 insuring the throw.

In Fig. 6 the piston is shown in its position when displaced completely towards the right, the walls of groove 41 being completely 40 in contact with the curve 35, while the walls of groove 40 are in contact at the left against the left hand narrow side of the curve 36. In Fig. 7 the piston is shown in its position when displaced completely towards the left when the compressing of the walls of the 45 groove towards the curves takes place in the reverse order to what has been explained above. In Fig. 8 is shown the displacement of the piston in an intermediate position and consequently also the intermediate position 50 of the curve 36 within the groove 40. The short axis of the curve 36 therefore corresponds to the length of the stroke and groove 40 is twice as wide as the short axis of the ellipse 36. In conformance with the 55 displacement of throw of the piston, the large axis of the ellipse of curve 35 must be three times as long as the short axis of the curve 36.

In Fig. 9 is shown a slight rotation of the 60 throw controlling member 34. By reason of this rotation it is no longer possible for the complete throw to be accomplished. In this figure is distinctly shown the space 42 which is being created between the curve 35 and the wall of the groove 41. This space corresponds to the diminution of the throw. If

the piston rotates to the maximum extent admissible in its displacement, which is shown in Fig. 9, the right hand wall of the groove 41 will contact with the right hand side of the curve 35, while the left hand wall of the groove 41 will diverge from the curve 35. On the other hand, however, the left hand wall of groove 40 is in contact with the left hand side of curve 36, and the right hand wall of the groove is free 70 and presents the space 43. In rotating the piston through 180° the compression is changed in reverse order. While when the throw controlling member is set in a normal position a fitting or bearing of the wall of the groove 41 takes place only against the curve 35 the fitting of the curves 35 and 36 with the walls of the grooves 40 and 41 will change on rotating the throw controlling member which of course, is tantamount 75 to a compulsory guiding also during the variation of the stroke by means of the throw controlling member. The variation of the throw and the diminution of the quantity of oil delivered which is ensuing therefrom, 80 will always be alike by reason of the compulsory motion and thus the places of consumption are supplied always with the same quantity of oil and that which is needed to 85 warrant efficient oiling.

In case the piston 20 for instance should not be needed for oiling, its throw may be completely discarded on rotating the throw controlling member from its full capacity position through an angle of 90° as is shown 90 in Fig. 10. The whole longitudinal axis of the ellipse 36 will spring in its entirety into the groove 40 while the fitting of the curve 35 with the walls of the groove 41 will cease. The piston receives the compulsory motion 105 only through the groove 40 extending vertically to the axis of the piston and therefore the piston remains axially un-displaced although still revolving round its axis.

A pump embodying this invention offers 110 considerable advantages over those of existing types in that it is extremely compact, there are only a small number of simple moving parts, all of which are easy to manufacture, and therefore the utmost reliability is 115 assured.

Variations in the details, when manufacturing the pump, will not influence the claims hereinafter set forth, nor will one thereby depart from the spirit and scope of our present 120 invention.

We claim:—

1. In a rotary piston pump, a driving member, a primary piston actuated from said driving member, and secondary pistons actuated for said primary piston, and means for varying the stroke of each piston separately. 125
2. In a rotary piston pump, a driving member, a primary piston actuated from said driving member, secondary pistons actuated 130

from said primary piston, slot and key coupling means between said primary and secondary pistons, and means for varying the stroke of each piston separately.

5 3. In a rotary piston pump, a driving member, a primary piston actuated from said driving member, secondary pistons actuated from said primary piston, slot and key coupling means between said primary and secondary pistons, means for varying the stroke of each piston separately, said means comprising grooves in each of said primary or secondary pistons, formed respectively at right angles and obliquely to the axis of the 10 respective piston, and adjustable studs engaging therewith.

4. In a rotary piston pump a driving member, a primary piston actuated from said driving member, secondary pistons actuated 20 from said primary piston, slot and key coupling means between said primary and secondary pistons, means for varying the stroke of each piston separately, said means comprising grooves in each of said primary or 25 secondary pistons, formed respectively at right angles and obliquely to the axis of the respective pistons, and adjustable studs engaging therewith, said studs being formed with elliptical bearing surfaces arranged at 30 right angles to each other, and adapted to engage respectively in said aforementioned grooves.
